U.S. Appl. No. 29/397,653, filed Jul. 19, 2011, Kim.

Primary Examiner — Karen E Eldridge Powers*(74) Attorney, Agent, or Firm* — Leason Ellis LLP**CLAIM**

The ornamental design for a bow tie and handkerchief retail combination, as shown and described.

DESCRIPTION

FIG. 1 is a front elevation view of a bow tie and handkerchief retail combination showing my new design;

FIG. 2 is a rear elevation view thereof;

FIG. 3 is a right side elevation view thereof; and,

FIG. 4 is a bottom plan view thereof.

The hanger and the interior edges of the handkerchief shown in broken lines are features that form no part of the claimed design.
